CLAIM

The ornamental design for a biological testing chip, as shown and described.

DESCRIPTION

FIG. 1 is a top, front, left perspective view of a biological testing chip, showing my new design;

FIG. 2 is a top, rear, right perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left-side elevation view thereof; and,

FIG. 8 is a right-side elevation view thereof.

In the drawings, the equal-length broken lines depict portions of the biological testing chip that form no part of the claimed design.
